ABSTRACT OF THE DISCLOSURE

This invention relates to an improvement in a shelf and/or tray which is adjustable in its length. The invention comprises a pair of sections, one telescoping within the other, to permit the length of the shelf to be adjusted, with a supporting bracket on each end thereof for securing to a wall or supporting surface to support the shelf in any adjusted length. The two sections may be inverted so that a shelf tray is formed having the same adjustability aforementioned. The following structure may be included with the foregoing. A pair of tubular members each secured to one of the support brackets are adjustable with the adjustability of the shelf for supporting or hanging towels, clothes hangers, and the like.

Summary of the invention

The invention includes an adjustable shelf, the length of which may be varied, which shelf may be inverted to form a tray shelf with upstanding border walls to prevent jars, bottles and other objects from being accidentally shoved or knocked off the tray shelf. It also may include an adjustable rod-like member on which towels and other objects may be hung.

One of the objects of this invention is to provide an improved shelf formed of a pair of sections, one telescoping within the other to permit the adjustment of the length of the shelf and where the supporting brackets for the shelf are detachably secured, one to each end of the shelf sections, which supporting brackets are in turn adapted to be secured to a wall or supporting surface. This provides an adjustable shelf of any desired adjusted length to be mounted on the wall, thereby eliminating the need for the manufacture of shelves of various prescribed lengths.

Another object of this invention is to provide a structure of the foregoing character where by inverting the shelf sections a tray shelf may be formed having upstanding flanges to prevent bottles, jars and like articles from being slid or pushed off the tray shelf.

Another object of this invention is to provide a telescopic member positioned below the shelf or tray for the purpose of hanging towels, clothes hangers, and the like.

Other objects will become apparent as this description progresses.

Brief description of the drawings

FIGURE 1 is a top plan elevational view of the invention partly in section;

FIGURE 2 is a front elevational view partly in section;

FIGURE 3 is a front view, partly in section, with the top member inverted to form a combination shelf tray;

FIGURE 4 is a view taken on lines 4—4 of FIGURE 2;

FIGURE 5 is a view taken on lines 5—5 of FIGURE 1;

FIGURE 6 is a view taken on lines 6—6 of FIGURE 1, and

FIGURE 7 is a perspective view of one of the support brackets.

Description of the embodiments

The adjustable top member, generally indicated at 10, which forms the shelf portion of the unit is best shown in FIGURES 1 and 2 and is formed of two sections 12 and 14, each preferably formed of metal. Section 12 comprises a horizontal wall 16, a downwardly extending front flange 18 which is reversely bent at its lower end to form a generally U-shaped lip 20. The rear of the horizontal wall 16 likewise has a rearwardly and downwardly extending flange 22 which is reversely bent at its lower end to form a generally U-shaped lip 23, similar to the lip 20 formed on the front flange 18. The front and rear lips 20 and 23 serve to form trackways 24 and 25 in which slides section 14 of the shelf. The outer end of section 12 is turned downwardly to form an end wall 26 and same is provided with an opening 28. The lower end of end wall 26 is reversely bent as at 27 to lie flat against the end wall.

Section 14 has a horizontal wall 29, a downwardly extending front flange 30 which is reversely bent at its lower end as at 32 and lies flat against the front flange. The rear of the horizontal wall 29 has a rearwardly and downwardly extending flange 34 which is reversely bent at its lower end as at 35 to lie flat against the rear flange. The outer end of section 14 is turned downwardly to form an end wall 36 and same is provided with a central opening 37.

The two sections 12 and 14 are interfitted, with section 14 telescoping into section 12, so that the front and rear flanges 30 and 34 of section 14 nest respectively within the front and rear flanges 18 and 22 of section 12 and the bottom ends of the flanges 30 and 34 of section 14 form runners which slide within the trackways 24 and 25 of the section 12. The two sections 12 and 14 may be moved inwardly towards each other to reduce the length of the combined shelf unit or they may be moved outwardly in relation to each other to a maximum extent to extend the length of the shelf.

A support bracket, generally designated by the numeral 40, is positioned at each of the opposite ends and mounted on a wall or vertical supporting surface. Each bracket supports one of the opposite ends of the telescopic shelf. The support brackets 40 are right and left hand and hence a description of one will suffice. The support bracket 40, formed preferably of metal, is shaped as best shown in FIGURE 7 and comprises an upper end wall 42, and an inwardly turned horizontal portion 44, with the metal extending downwardly from the inner end of the horizontal portion to form the lower end wall 46. The metal forming the lower end wall 46 is then turned inwardly to form an inclined front portion 48 and then turned upwardly to form an inside portion 50 which extends parallel to the outside end wall 46 of the bracket. The lower end wall 46 at its rear is bent inwardly at right angles to the end wall to form an extension 52 which is provided with a bayonet-type slot 54 adjacent the top and an opening 56 adjacent the bottom. The slot and opening 54 and 56 receive screws 57 or like fastening elements which secure the support brackets 40 to the wall or vertical support. An L-shaped flanged 58 is secured or brazed at its bottom to the horizontal portion 44 and said flange forms the upper front wall of the support bracket. The upper edge of the flange 58 and the upper edge of the upper end wall 42 are turned inwardly and downwardly to eliminate any sharp edges.

The inside portion 50 of the support bracket has an enlarged annular opening 60 for the purpose of receiving one of the ends of the telescopic tubular member generally indicated at 62. The telescopic tubular member

62 comprises a pair of tubular members 63 and 64 of different diameters so that the tubular member 63 telescopes into member 64. The outer end of each of the tubular members is received in its respective opening 60 and is held therein by a fastening screw 66 or the like passing through the front inclined portion 48 and through an opening in the tube to secure the tube to said support bracket, as best seen in FIGURES 5 and 6. The telescopic tubes are adjustable and may be extended or reduced in length to conform to the adjustable length of the shelf.

As best shown in FIGURES 1 and 2, the opposite ends of the shelf portion are supported in the upper portion of the support brackets, with the opposite ends of the shelf portion nesting within the confines of the upper ends of the bracket and resting on the horizontal portions 44. When the support brackets are secured to the wall the shelf is confined at its forward end by reason of the front wall 58 and at its rear by the wall structure or vertical support to which the brackets are secured. To prevent removal of the shelf portion from the support brackets a fastening screw 68 passes through an opening 70 in the end wall 42 of the bracket and through either one of the aligned openings 28 or 37 in the respective end walls of each of the shelf sections. With the fastening screws secured the shelf cannot be lifted or removed from the support bracket arms without unscrewing the fastening members.

If it is desired to use the shelf as a tray the two sections in their telescopic position are turned upside down 30 or inverted so that a tray is formed from the two sections, as best shown in FIGURE 3. The tray would be extensible and contractible in the same manner as previously described, however, in the tray position there are upstanding front and rear walls which extend upwardly of the horizontal portions of the sections. In the tray position what was formerly the front and rear of the shelf sections are reversed and the former rear walls become the front wall of the tray. The tray is supported and secured to the support brackets in the same manner as 40 previously described. Thus, the two sections may be used either as a shelf in the normal manner or by turning them upside down serve as a tray. In the tray manner they also serve as a shelf, however, the tray has the additional advantage in that it prevents bottles, jars and the like from being accidentally pushed off the front, rear and opposite ends of the tray. The telescopic tubular member may be used to hang towels or support clothes hangers on which clothes may be hung.

I claim:

1. A structure of the character described comprising, a pair of supporting brackets adapted to be mounted on

5 a wall or supporting surface, each of said supporting brackets having an upper portion provided with a vertically extending end wall and a vertically extending front wall and a horizontal wall, a plurality of sections forming a shelf portion, one section being telescopically interengaged with the other to permit adjustment of the length of the shelf portion, the outermost ends of the two outermost sections each adapted to be supported on one of said supporting brackets and to rest on the horizontal wall of the bracket with the ends of the shelf portion confined within the end wall and front wall of the bracket, said brackets each having a downwardly extending lower wall extending below the horizontal wall.

10 2. A structure as defined in claim 1 in which each of the sections has an end wall with adjacent end walls of the bracket and section having aligned openings to receive a fastening element to detachably secure the shelf to the brackets.

15 3. A structure as defined in claim 1 in which the sections each have a horizontal wall and spaced downwardly front and rear walls extending longitudinally thereof, and when the sections are inverted form a tray shelf with the front and rear walls extending upwardly of the horizontal wall of the sections.

20 4. A structure as defined in claim 1 in which the downwardly extending lower wall of the bracket supports a telescopic tubular member which is adjustable with the length of the shelf portion whereby a towel or the like may be hung on said telescopic tubular member.

25 5. A structure as defined in claim 1 in which the bottom of the lower wall of the bracket has an inwardly and upwardly turned inner wall spaced from the lower wall and substantially parallel thereto and which is provided with an opening to receive the end of a tubular member.
